UNITED STATES PATENT OFFICE

ROBERT G. WULFF, OF LOS ANGELES, CALIFORNIA

EXPLOSIVE AND PROCESS FOR MAKING

No Drawing.

Application filed March 7, 1929. Serial No. 345,249.

This invention relates to an explosive which is capable of becoming harmless within a reasonably short interval after being loaded into a bore hole.

One of the objects of this invention is to produce such an explosive having the added advantage of producing less and less carbon monoxide the later it is fired. Other explosives of this class, the liquid oxygen explosives, produce more and more carbon monoxide the later they are fired, because the oxidizing agent evaporates very rapidly.

Another object of my invention is to produce an explosive which may be easily mixed together at place of use from relatively harmless and cheap materials.

My explosive comprises a solid oxidizing agent and a volatile combustible. Liquid oxygen explosives comprise a volatile oxidizing agent and a fixed combustible.

An advantage of my explosive is that the oxygen-bearing constituent is solid, and therefore easy to transport without loss. It is the oxygen-containing portion that is expensive in a common explosive. I provide a volatile combustible, such as butane, which is very cheap. It can furthermore be held indefinitely in liquefied form under pressure, in contrast to liquid oxygen.

Another advantage of my explosive over those using liquid oxygen is that I can fix the boiling-point of the combustible to suit the climate or the nature of the work, so as to control the rate of evaporation. I do this by adding heavier or lighter hydrocarbons.

In my explosive, the oxidizing agent may be a chlorate or perchlorate. It may alternatively be ammonium nitrate or other nitrate, or even a peroxide, such as calcium or barium peroxide. The combustible is a normally gaseous hydrocarbon, such as propane or butane, preferably the latter. Very volatile casing head gasoline or petroleum ether is also suitable, but pure liquefied butane is

preferred. Also a mixture of hydrocarbons containing butane and lighter constituents may be used.

My explosive is produced by wetting the oxidizing agent with the combustible to saturation, over saturation, or undersaturation, in respect to either the capacity of the oxidizing agent for physically holding the combustible or for oxidizing it. I prefer to oversaturate the oxidizing agent in both respects since the volatility of the combustible soon diminishes the excess of the latter. The saturation is preferably accomplished by dipping a cartridge of oxidizing agent, in a porous or open envelope, such as of cloth or paper, completely into a container full of liquefied combustible. The oxidizing agent, now saturated, is then lifted out and thereafter used as an explosive as soon as possible; that is, loaded into the bore hole approximately within half an hour. The explosive will lose its power of exploding or at least of exploding violently, if the firing is attempted after a longer interval than an hour. The exact time depends upon the tightness to which the bore hole is tamped, and other factors, such as the size of the bore hole and the volatility of the combustible. While I may fire the explosive with only a fuse or electric squib when only low explosive power is required, I find that for high explosive force it is necessary to explode the mixture with a detonator, preferably a No. 8 fulminate detonator.

Under some conditions, for instance, in hot climates, I find it advisable to alter the composition of my explosive to the extent of adding an absorbent material to the oxidizing agent before mixing the combustible therewith. Such absorbents are preferably incombustible, such as silica gel, kieselguhr, or adsorbent clay. I may use combustible adsorbents such as activated charcoal, wood flour or sawdust, but only in small percentages, that is, 5% by weight or less of the oxidizing

agent. The object of using only small amounts is to insure that the residue of the explosive, after evaporation of the volatile combustible, will not possess any substantial explosive properties. Incombustible adsorbents may be used in larger amounts, however.

The compositions which my explosive may have, in percentage by weight, lie within the following ranges:

	Per cent
Oxidizing agent	60-95
Absorbent	1-15
Volatile combustible	5-40

15 Proportions are intended to be varied according to the kind of work to be done and the specific material employed.

16 The mixture should be so adjusted so that at the time it is to be fired, there is no excess or deficiency of combustible with reference to the amount of oxidizing agent present.

17 The container necessary may or may not be combustible. It must allow the volatile combustible to leave the charge as it evaporates. This may be accomplished by having a container with a hole near the top communicating to the atmosphere. It may also be done by making the container wall of suitable porosity therefor, while at the same time preferably retaining the combustible as long as it is in the liquid phase.

18 After the mixing has once taken place, the combustible is not to be hindered from evaporation except by the presence of an absorbent or by the presence of the tamping in the bore hole. Both of these do not absolutely prevent escape of the combustible. I may use a permeable container for my explosive, however, such as a cardboard cylinder, paper wrapping, cloth bag, or even asbestos bag. The latter, while expensive, has the advantage that the oxidizing charge may be packaged and shipped out of contact with any combustible substance whatever so that fire risk is eliminated.

19 In order to diminish the hygroscopic tendencies of any of my oxidizing agents, I may coat the particles thereof with any of the usual protective coatings, such as nitro-cellulose, dinitrotoluene, trinitrotoluene, etc. My oxidizing agents may be varied as to their particle size from crystals the approximate size of a pea down to a finely ground condition.

20 In general the more finely divided the oxidizing agent, the quicker and more powerful will be the explosive.

21 Instead of using a single oxidizing agent I may mix those which I have enumerated, but a chlorate or peroxide should never be mixed with ammonium nitrate. I may substitute for part of expensive oxidizing agents, however, such as perchlorates, up to 50% of cheaper ones, such as sodium nitrate.

22 In cases where an explosive of the maxi-

mum power is wanted, regardless of expense, I may incorporate into my explosive up to 10% by weight of finely divided aluminum powder or flake.

23 I may also find it desirable in the case of cold climates to provide an extremely volatile hydrocarbon liquid, such as a mixture of propane and butane, even with small proportions of ethane.

24 I claim as my invention:

25 1. An explosive comprising an unsealed combustible liquid more volatile than pentane and a solid oxidizing agent.

26 2. An explosive according to claim 1 in which the volatile combustible liquid is a hydrocarbon normally gaseous at atmospheric temperature and pressure.

27 3. An explosive comprising a mixture of a solid oxidizing agent and a liquefied normally gaseous mixture of hydrocarbons substantially open to the atmosphere.

28 4. An explosive comprising a perchlorate and a liquefied normally gaseous mixture of hydrocarbons substantially open to the atmosphere.

29 5. An explosive comprising a perchlorate, an alkali-metal nitrate and a liquefied normally gaseous mixture of hydrocarbons substantially open to the atmosphere.

30 6. An explosive comprising a solid oxidizing agent, an absorbent and a substantial proportion of an unconfined petroleum hydrocarbon liquid more volatile than pentane.

31 7. An explosive comprising a solid oxidizing agent, a non-combustible absorbent and a substantial proportion of an unconfined petroleum hydrocarbon liquid more volatile than pentane.

32 8. An unsealed explosive comprising an oxidizing salt and a volatile combustible liquid a substantial proportion of which is liquid butane.

33 9. An explosive having a liquefied volatile oxidizable constituent and capable of losing its explosive power after a few hours exposure to atmospheric temperature and pressure by reason of the evaporation of its said oxidizable constituent.

34 10. An explosive comprising a solid oxidizing agent and an initial excess of a combustible liquid more volatile than pentane over that required for complete consumption of the oxygen of the oxidizing agent, said explosive being capable at atmospheric conditions of temperature and pressure of being altered as to its oxygen balance so that more complete combustion will occur after an interval of exposure to such atmospheric conditions.

35 11. An explosive comprising an oxidizing salt, finely divided aluminum and a substantial proportion of a liquid hydrocarbon more volatile than pentane.

36 12. An explosive comprising an oxidizing salt, silica gel and a substantial proportion

of a liquid hydrocarbon more volatile than pentane.

13. An explosive comprising an oxidizing salt, silica gel, aluminum powder and liquid butane.

5 14. An explosive comprising an oxidizing salt the particles whereof have a protective coating and a substantial proportion of a liquid hydrocarbon more volatile than pentane.

10 15. The process of making an explosive adapted to soon lose its explosive power under atmospheric conditions which comprises dipping a charge comprising an oxidizing salt contained in a porous fabric container into a vessel containing a substantial quantity of a liquefied mixture of hydrocarbons more volatile than pentane, and then withdrawing said charge.

15 20 16. The process of making an explosive capable of soon losing its explosive power under atmospheric conditions which comprises wetting a charge comprising an oxidizing salt held in a porous container, with 25 a substantial quantity of a hydrocarbonaceous liquid more volatile than pentane.

In testimony whereof, I have hereunto set my hand at Los Angeles, California, this 2nd day of March, 1929.
